JAMES D. BRYSON, OF NEWCASTLE, PENNSYLVANIA.

Letters Patent No. 68,945, dated September 17, 1867.

IMPROVEMENT IN WATER-WHEELS.

The Schedule referred to in these Letters Patent and making part of the same.

TO ALL WHOM IT MAY CONCERN:

Be it known that I, JAMES D. BRYSON, of Newcastle, in the county of Lawrence, and State of Pennsylvania, have invented a new and useful Improvement in Turbine Water-Wheels; and I do hereby declare the following to be a full, clear, and exact description of the nature, construction, and operation of the same, reference being had to the accompanying drawing, making part of this specification.

This invention consists, first, in novel means for adjusting the buckets to correspond with the adjustment of the gates, in order that such relation may be maintained between the two, as to position or angle, as will insure the most effective operation under the variations in the amount of acting water, which are due to the adjustment of the gates or inlet; second, in the employment of slotted arms, through the medium of which the gates are opened simultaneously and permitted to close independently, in order that obstruction to the motion of one or more buckets shall not interfere with the operation of the remainder.

Figure 1 is a horizontal section of a turbine-wheel and its accessories illustrating my invention.

Figure 2 is a sectional elevation of the same, the section being made on a vertical plane coincident with the axis of rotation.

Figure 3 is a side elevation, and

Figure 4 is a detached view illustrating the mode of adjusting the gates.

Similar letters of reference indicate corresponding parts in the several figures.

A may represent the framing, in which the turbine B, with its spindle C, may be mounted to rotate in customary manner. The buckets B' form oblique abutments, against which the water from the external casing is permitted to impinge in order to impart rotation to the wheel B, upon which the said buckets have pivotal attachment. The amount of water allowed to act upon the buckets B' in a given time is regulated by the gates D, which are attached by pivots to the stationary castings E E. The water exerts a simultaneous action upon the buckets B' all around the periphery of B, and passing between the buckets it descends through the central discharge space G, fig. 2. The gates D are "opened" or "closed" to enlarge or diminish the inlet spaces between them, by the rotation of the annulus H, (see figs. 2 and 3,) which is connected with the gates D by means of the arms I, and which is operated by means of the cogged segment J and the pinion K on the shaft K', the latter being turned by means of the wheel K². The inner extremities of the arms I are suitably jointed to the annulus H, while the outer ends of said arms are formed with slots h, which receive the pins d, whereby the arms are connected to the gates. When the annulus H is turned so as to project the arms I beyond the periphery of E, the gates D are opened simultaneously, and the inlet spaces enlarged in consequence of the direct action of said arms upon the pins d, but when the arms I are retracted by a reverse motion of the annulus H the slots h adapt the gates D to be closed, thereby diminishing the inlet spaces by the pressure of the water in the surrounding casing, each gate having freedom to close independently of the others. Hence any object which may obstruct one or two of the gates will not interfere with the desired adjustment of the remainder. In order to secure the greatest power with a given amount of acting water, I have found it requisite to change the position of the buckets B' as often as the gates D undergo a new adjustment, thereby maintaining that relative position of the buckets and gates which insures the most effective impingement of the water. This adjustment of the buckets I effect by the means which I shall now proceed to describe.

L L' represents a two-part staff or rod, to accommodate which the turbine-spindle C is made hollow, as shown in figs. 1 and 2. The spindle C is also slotted at e, to permit the vertical play of a rod, l, which attaches a vertically adjustable collar, M, to the lower extremities of L L'. N N N represent a series of radial arms suitably pivoted at their opposite extremities to the collar M and buckets B'. The upper end of L is threaded and furnished with a jam-nut, o, which, being turned by means of a hand-wheel, O', to which it is keyed, serves to raise or lower the staff L L', together with the collar M. The collar M acting through the arms N serves to open or close the buckets, as the case may be, in order to vary their position to correspond with the gates D. A swivel-joint at l' adapts the upper part of the staff L to move the lower part L' vertically without imparting its rotating motion thereto.

Having thus described my invention, what I claim as new therein, and desire to secure by Letters Patent, is—

1. The combination, in a turbine water-wheel, of the adjustable gates or chutes D, and adjustable buckets

or issues B', whereby the area of the issues may be varied to correspond with the regulated capacity of the inlets or chutes.

2. In combination with the above the slotted adjusting-arms I I', applied so as to open the gates simultaneously and permit them to close independently, so as to prevent the obstruction of one or more gates from interfering with the operation of the remainder.

3. The combination, with the adjustable buckets B', of the adjusting-staff or screw L L', and swivel l', applied and operating substantially as described.

4. The combination of the staff or screw L L', and swivel l', hollow slotted spindle E, jointed arms N, and ring or collar M, arranged as described, and operating so as to permit the buckets to be adjusted while the wheel is in motion, as set forth.

JAMES D. BRYSON.
